UNITED STATES PATENT OFFICE

122,152

DESIGN FOR A DISPLAY BOX FOR JEWELRY OR THE LIKE

Jack G. Allen, Chicago, Ill., assignor to F. H.
Noble & Co., Chicago, Ill., a corporation of Illinois

Application June 14, 1940, Serial No. 93,014

Term of patent 7 years

To all whom it may concern:

Be it known that I, Jack G. Allen, a citizen of the United States, residing at Chicago, in the county of Cook, State of Illinois, have invented a new, original, and ornamental Design for a Display Box for Jewelry or the like, of which the following is a specification, reference being had to the accompanying drawing, forming a part thereof.

In the drawing: Fig. 1 is a perspective view of a display box for jewelry or the like, showing my new design, with the cover in raised position;

Fig. 2 is a top plan view;

Fig. 3 is a front elevational view; and

Fig. 4 is an end elevational view of the same.

I claim:

The ornamental design for a display box for jewelry or the like, as shown.

JACK G. ALLEN.
